REFINING OF PETROLEUM OILS

Eric B. Hjerpe, Pittsburgh, and William A. Gruse,
Wilkinsburg, Pa., assignors to Gulf Research &
Development Company, Pittsburgh, Pa., a cor-
poration of Delaware

No Drawing. Application November 2, 1934,
Serial No. 751,258

6 Claims. (Cl. 196—17)

This invention relates to the refining of petroleum oils and it comprises improved unitary methods of extracting and dewaxing such oils with the aid of solvents wherein the oil is first extracted with a mixture containing ethylene dichloride, benzol and SO_2 and then the refined oil is dewaxed in the presence of the benzol and ethylene dichloride; the SO_2 being removed from the oil after the mixture has been stratified into an oil layer and a solvent layer but before the oil diluted with the remaining solvents is subjected to temperatures sufficient to precipitate the wax; all as more fully hereinafter set forth and as claimed.

Some petroleum oils primarily are composed of paraffinic oils, naphthenic oils and petrolatum which is a mixture of high and low melting waxes and resins. It is known that by dewaxing the oil and removing the poly-naphthenic materials, oils improved for certain uses can be obtained.

Petroleum oil being more or less a heterogeneous mixture, its behavior when treated with solvents varies with the particular solvent. Some solvents such as benzol and naphtha are completely miscible with the oil but when the solution is cooled the waxes or petrolatum become insoluble at certain temperatures and may be separated from the oil diluted with the solvent. Such solvents are known in the art as good solvents because they hold the oil in solution even at low temperature.

On the other hand there is another class of solvents which are not completely miscible with the oil. Such solvents when admixed with the oil at elevated temperatures do form homogeneous miscible mixtures. But when the mixture is cooled below a definite miscibility temperature, it stratifies into an oil layer and a solvent layer. The poly-naphthenic portion of the oil is soluble in these solvents and appears in the solvent layer. The paraffinic oils are insoluble and constitute most of the oil layer when it is formed.

It has been proposed to dewax petroleum oils by mixing the oil with such good solvents and cooling the mixture to precipitate the wax. The wax is separated from the oil diluted with solvent either by filter pressing or centrifuging.

Likewise, it has been proposed to refine oils by solvent extraction using the other type of solvents which function as differential solvents. In these solvent extraction processes the oil and the solvent are mixed and then the mixture brought to temperatures at which the oil layer and the solvent layer are not miscible. Alternatively, the oil and solvent may be mixed at the temperature at which separation is to be effected, equilibrium being attained by agitation. The oil layer is separated from the solvent layer containing extracted naphthenic oil and the oil layer freed of

residual solvent. An equivalent continuous process may be employed.

Although it is necessary to remove both the wax and the naphthenic bodies to obtain a completely refined oil, heretofore no single process was available by which both of these refinements could be obtained in a simple unitary manner. Of course, the oil could be first dewaxed and then refined or vice versa but each of the procedures is entirely independent of the other and constitutes a separate process employing distinct solvents or solvent mixtures. Further, the prior dewaxing and solvent extraction processes in commercial practice are subject to one or more disadvantages or difficulties. In any event, in prior practice, it was necessary to completely remove the dewaxing solvent before proceeding with the solvent extraction or vice versa.

By the present invention we obtain a substantially complete refining of the oil in an improved manner which is free of the disadvantages and difficulties of the prior methods. In the present process the solvent extraction and the dewaxing are effectively correlated into a unitary simple process having many advantages.

In the Livingstone Patent No. 1,848,636, an advantageous method of dewaxing oils with a mixture of benzol and ethylene dichloride is disclosed. In the present processes, the principles of that process are used to advantage in a complete process in refining the oil. The present process is in a sense an improvement upon the Livingstone process.

We have found that by extracting the oil with a mixed solvent containing ethylene dichloride, benzol and SO_2 , improved oils are obtained and the oil layer, after separation from the solvent layer and removal of SO_2 , is ideally suited for dewaxing by the procedures of the Livingstone patent since it constitutes a solution of oil to be dewaxed in the solvent of the Livingstone process.

Likewise the present methods constitute an improvement upon the solvent extraction methods disclosed and claimed in our copending applications Serial Nos. 721,256 and 751,259. In Serial No. 751,256 we disclose processes for extracting oils with ethylene dichloride wherein the ethylene dichloride is mixed with the oil and the mixture cooled to a suitable temperature to effect stratification. In Serial No. 751,259 we disclose some what similar processes wherein a mixture of ethylene dichloride and SO_2 are used in extracting the oil.

In the present invention, we gain, in addition to all the advantages of our other processes described in said applications, further advantages and improvements.

Oils have been extracted with SO_2 alone or in admixture with benzol, but those processes have not been entirely satisfactory in commercial prac-

tice and do not give the advantages obtained in the present process.

Our composite solvent used for solvent extraction has many advantages. It is composed of 5 ethylene dichloride, benzol and SO₂, each of these ingredients cooperating with the others in a correlated manner to give superior results. Our composite solvent easily penetrates the oil to give a substantially complete extraction of the naph- 10 thenic material. It is highly selective in its action and a maximum of naphthenic bodies is removed with a minimum loss of paraffinic oil in the present process.

In the present processes, the oil is mixed with 15 the composite solvent and permitted to stratify.

After the oil layer has been stratified and separated from the solvent layer, the SO₂ can easily be removed, leaving an oil dissolved in the ethylene dichloride-benzol mixture. This solution 20 might be submitted directly to chilling and wax separation, but for proper drainage of liquid from the wax crystals it is desirable to increase the proportion of ethylene dichloride-benzol mixture present.

25 The miscibility temperature of our new composite extraction solvent is such that it can be easily mixed with the oil at ordinary temperatures and then stratified directly. Thus, solvent extraction can easily be first performed and then 30 the oil dewaxed in a simple unitary manner fully utilizing the advantages of these particular solvents.

In practicing the present processes, the oil is mixed with a composite solvent containing ethylene dichloride, benzol and liquid SO₂ at ordinary 35 temperatures, usually 75° F. The mixture is permitted to stratify into an oil layer and a solvent layer and the oil layer is separated from the solvent layer. The oil layer may be subjected to 40 one or more similar extractions, or the process may be a continuous one, as for instance by the countercurrent method.

The final raffinate layer so obtained (oil layer) is then flash distilled in a vacuum to remove SO₂. 45 The raffinate solution so obtained, which is substantially free of SO₂, is then diluted with more of the composite solvent, usually a 70:30 mixture of ethylene dichloride and benzol. The diluted mixture is then cooled to temperatures 50 sufficient to precipitate the wax. The wax is filtered off and the filtrate is then freed of solvent by distillation.

In these processes, a composite solvent containing 55 70 parts of ethylene dichloride and 30 parts benzol is advantageous. However, that ratio may be varied and composite solvent mixtures containing ethylene dichloride and benzol in ratios between 90:10 and 50:50 can be used.

Of course, the amount of sulfur dioxide added 60 to the composite solvent to produce the mixed solvent necessary to effect stratification, may be varied in commercial operation. It is advantageous to use sufficient sulfur dioxide to give sulfur dioxide-ethylene dichloride ratios between 65 90:10 and 50:50. An advantageous mixed solvent useful in the extraction step has the following composition:—21 parts of ethylene dichloride, 9 parts of benzol and 70 parts of SO₂.

The oil layer which is subjected to the dewax- 70 ing operation is the oil layer obtained in the stratification step after the SO₂ has been removed. It contains some ethylene dichloride and benzol in approximately the original ratio; in removing the SO₂, some of the composite solvent is lost but the ratio of its components is not ma-

terially changed; this may be adjusted if necessary. In dewaxing, it is advantageous to obtain a dilute oil in which the diluent solvent contains ethylene dichloride and benzol in approximately the ratio 70:30. In the usual practice, the 5 ethylene dichloride is present in major amounts.

In these processes, the solvent extraction or stratification can be effected at temperatures between 0° F. and 125° F.

In the dewaxing step, lower temperatures are 10 used. Dewaxing may be effectively obtained at temperatures between -30° F. and +10° F. The temperature to be employed will depend on the extent of wax removal desired. To obtain an oil with a pour point of 0° F. a filtering temperature 15 of minus 5° F. to minus 10° F. is suitable.

In these processes, an improved dewaxed refined oil is obtained and as byproduct, there is also obtained petrolatum or waxes and a useful naphthenic oil. The solvent removed from the 20 oil layer and from the solvent layer by distillation is recovered and re-used in the processes.

This invention is broadly applicable to refining petroleum oils and various embodiments thereof may be used in refining particular oil stocks to 25 produce special refined oils. One advantageous embodiment of this invention which is typical and illustrative is as follows:—

Example 1

30

100 parts of overhead cylinder stock from Oklahoma crude is mixed at 75° with 9 parts of benzol, 21 parts of ethylene dichloride, and 70 parts of liquid SO₂. After a homogeneous mixture is obtained, it is permitted to stand until 35 clean stratification into an oil layer and a solvent layer is obtained. Usually a half hour at 75° F. is sufficient.

After stratification, the lower solvent layer is drawn off. The upper oil layer remaining in 40 the apparatus is subjected to three more extractions in the same manner.

The final raffinate so obtained (upper oil layer) is then flashed at 75° F. in a vacuum of 50 mm. to remove practically all the SO₂. The oil layer 45 so obtained is then ready to be dewaxed.

The oil layer so freed of SO₂ is then mixed with 300 parts of a 70:30 mixture of ethylene dichloride and benzol. After a homogeneous mixture is obtained, it is cooled to 0° F. over 50 a period of 2 hours. By this treatment the wax is rendered insoluble and is precipitated. The so cooled mixture is then filter-pressed at about 0° F. to remove the wax. The filtrate separated from the wax is then freed from the dewaxing solvent by distillation up to 400° F. to obtain an improved dewaxed refined oil. Fifty-six parts of a refined oil are obtained.

The improvement in the oil obtained by these processes is clearly discernible by comparison 60 of its properties with those of the oil stock, as follows:

	Original oil	Refined oil
Specific gravity (60° F.)	0.927	0.9030
Viscosity Saybolt at 210° F.	130 Sec.	111 Sec.
Viscosity index	70	81
Viscosity gravity constant	0.853	0.823
Pour point	110° F.	5° F.

The solvent contained in the solvent layer in the extraction step is likewise recovered by distillation. The recovered solvent is re-used in the process. As byproduct, there is recovered from 75

this distillation 35 parts of useful naphthenic oil.

Also, from the filter pressing operation, there is recovered 9 parts of useful petrolatum. This petrolatum can be further refined to obtain several grades of commercial wax.

In the commercial practice of these processes, suitable heat exchange is effected between the cold liquids and the hot liquids and vapors incident to the process.

10 In lieu of the exact procedure employed in the example given ante, the process may be varied as has been indicated in the foregoing disclosure, if desired.

15 The present processes are particularly advantageous for refining of relatively paraffinic stocks moderately low in wax content. With such stocks the extraction can be effectively performed at say about 75° F. and then the raffinate dewaxed at a suitable temperature without precipitating 20 oil with the wax, by these unitary processes, as described in detail ante.

What we claim is:—

1. The process of refining petroleum oils which comprises first extracting the oil at a relatively 25 high temperature with a composite solvent comprising ethylene dichloride, benzol and SO₂, separating the resultant oil and solvent layers, then removing SO₂ from the oil layer and chilling the resultant substantially SO₂-free mixture to a relatively low temperature at which wax will precipitate and removing the precipitated wax from the oil in the presence of ethylene dichloride and benzol.

2. The process of claim 1 wherein said extraction is effected at temperatures between 0° F. 35 and 125° F. and said dewaxing is effected at temperatures between 10° F. and minus 30° F.

3. The process of claim 1 wherein said mixed solvent contains ethylene dichloride and benzol 40 in ratios between 90:10 and 50:50, said mixture containing sufficient SO₂ to cause clean stratifi-

cation at the extraction temperature, the ratio of SO₂ to ethylene dichloride being between 90:10 and 50:50.

4. The process of claim 1 wherein during said dewaxing sufficient benzol is present in addition 5 to the ethylene dichloride to prevent co-precipitation of paraffinic oil with the wax.

5. As an improvement in refining petroleum oils by which extraction and dewaxing with solvents is effected in a unitary manner, the improved process which comprises extracting the oil at about 75° F. with a mixed composite solvent comprising 9 parts benzol, 21 parts ethylene dichloride and 70 parts SO₂, separating the oil layer from the solvent layer thus formed, removing the SO₂ from said oil layer, diluting the so treated oil layer with additional amounts of a mixed solvent comprising 70 parts of ethylene dichloride and 30 parts of benzol, cooling the diluted mixture to approximately 0° F., separating 15 the wax from the oil diluted with said composite solvent at said temperature and distilling the filtrate thus obtained to remove the said composite solvent and recover an improved de-waxed oil.
